INVENTOR.

PAUL W. FENTON

BY Homer Underwood

ATTORNEY.

UNITED STATES PATENT OFFICE.

PAUL W. FENTON, OF NEW YORK, N. Y.

OIL-DISPENSING PUMP.

Application filed April 8, 1925. Serial No. 21,506.

To all whom it may concern:

Be it known that I, PAUL W. FENTON, a citizen of the United States, residing at the city of New York, in the county of New York, State of New York, have invented certain new and useful Improvements in Oil-Dispensing Pumps, of which the following is a specification.

My invention relates particularly to the class of pumps used for dispensing lubricating oils and the object thereof is to provide a simple, reliable and efficient device of this character.

Lubricating oils, particularly for automobile use, are usually distributed to filling stations in barrels or special containers. Various means have been provided for retailing such oils to consumers, measuring the oil in small quantities, and, in some instances, pumps have been provided for pumping the oil from such barrels or containers into a measuring device. In such pumps heretofore used, the oil drips from the discharge nozzle after the operation of the pump is completed and the pump is often operated by unauthorized persons just for the amusement of seeing the oil flow, and for these reasons means have been provided to return the drip or oil needlessly pumped, back to the container, but such means were either cumbersome or permitted the oil to become contaminated with foreign matter before its return to the container. The object, therefore, of my invention is to prevent the drip of oil after the operation of the pump and to lessen the liability of the pump being operated for no useful purpose.

A further object of my invention is to provide means for automatically closing the outlet at the instant the container being filled is removed from its filling position.

These primary objects, and others, perhaps of a subordinate nature, I accomplish by means hereinafter described and shown in the accompanying drawings which form a part of my specification.

In the accompanying drawings Fig. 1, is a vertical sectional view of a measuring pump embodying features of my invention.

Fig. 2, is a detail view, partially in section on line II-II of Fig. 1, showing the rack and pinion for operating the piston of the pump.

Fig. 3, is a view in elevation from the left

of Fig. 1, illustrating details of the discharge nozzle.

Fig. 4, is a section of the discharge nozzle showing the valve in open position.

Fig. 5, is a section showing a modified form of my discharge nozzle.

A preferred type of pump comprises a piston 1, adapted to reciprocate in the cylinder 2 and to be actuated by the pinion 4 having teeth meshing with the teeth of the rack 3. This pinion is mounted upon a shaft 5 to one end of which is also secured a hand-crank 6. The lower head 7 of the cylinder 2 is provided with a threaded portion 8 for the purpose of securing the pump in the head of the container from which oil is to be pumped, the container not being shown in the drawings. A pipe 9 extending to substantially the bottom of the container and secured in the cylinder-head 7, affords a means through which the oil may be drawn from the container when the piston is moved upward. As the oil is removed from the container air must be admitted thereto to replace the oil removed, hence I have provided one or more vents 10 in the cylinder-head 7, thus avoiding the need of a vent in the container.

The cylinder is provided with an upper head 12 which is secured to the lower head 7 by means of standards 13. The upper head may be formed with an extension 14 to serve as a passage for the oil and affording space in which the rack may be reciprocated. The upper head is apertured to permit the passing of the rack therethrough and also in addition thereto leaving space sufficient for the passage of the oil from the cylinder to the extension of said head. At the top of the extension or pipe 14 is inserted a set-screw 15 for the purpose of adjustably limiting the travel upwardly of the rack 3. To this extension or pipe 14 is secured by threaded or other suitable engagement a short pipe 16 and on one end of the pipe 16 is secured the nozzle assembly, though manifestly the pipe 16 may be omitted and the nozzle assembly secured directly to the pipe 14.

The nozzle assembly comprises a hollow cylindrical member 17, the lower side of which is provided with a lug 18 to which is pivoted in any suitable manner an arm 19. The outer end of the member 17 and at the top thereof, is apertured to receive a nut 20

which in turn is also apertured in a suitable manner to receive the spring 21. In the lower portion of the outer end of the member 17 is an opening 22 which is closed by 5 the valve-head 23 and may be opened to permit the passage of oil therethrough when the valve-head 23 is lifted from its seat. In the lower portion of the member 17 is secured by threaded engagement a cylindrical member 24, open at the bottom, and which may be termed a sleeve in which there are openings 25 to receive a spanner wrench by which it may be tightened. Within the sleeve 24 is mounted an expansible metal diaphragm 26. A discharge outlet tube 27 is provided with a flange 28 against which the lower edge of the diaphragm is pressed by means of a nut 29 which is locked in place by a set-screw 30. The outlet tube 27 thus 10 extends through the central portion of the diaphragm and terminates a short distance below the valve head 23 and is provided with openings 31 to permit the oil to pass from the diaphragm into the discharge tube 27. The valve head 23 is provided with a stem 32 which extends into the upper end of the discharge tube 27. The arm 19 is bent upward and is provided with a slot near its upper end at 33, into which is fitted a 15 guide-screw 34 which is secured by threaded engagement to the outer end of the member 17. The arm 19 is also apertured to receive the discharge tube 27, sufficient clearance being allowed to accommodate for the 20 changed position of the lever when the latter is forced upward for the purpose hereinafter described.

In Fig. 5, I have illustrated a modified form of my nozzle assembly in which I have substituted a coil spring 35 for the expansible diaphragm necessitating certain other changes among which are: that the stem of the valve is lengthened and the lower end 36 is bored out and openings 37 are provided therein to permit the passage of oil from the sleeve 38 to the bore 36 in the stem 32. A member 39 is adapted to fit within the sleeve 38 and is bored to form a discharge outlet 40 and also to suitably receive the 45 lower end of the stem 32. A space 41 between the lower end of the stem 32 and the upper end of the discharge outlet is provided for the purpose hereinafter described. In this construction is also provided a piston ring 42 which is held in a groove in the member 39 and serves to prevent the passage 50 of oil between the sleeve 38 and the member 39. The opening 22 forming the seat for the valve head is, in this construction, in the upper end of the sleeve 38, and the other portions of the nozzle assembly substantially the same as first above described.

From the foregoing description the operation of my invention will be readily understood. When the valve 23 is in closed posi-

tion as shown in Fig. 1, removal of any oil from the pump is prevented until the valve is first opened. When it is desired to remove oil through the discharge nozzle a receptacle in which the oil is to be received is placed 70 under the discharge nozzle and pressure is applied in an upward direction. By reason of the edge of the receptacle coming in contact with the arm 19, if the pressure is applied to the receptacle, the force will be 75 transmitted through the receptacle to the arm and the arm will be forced upward carrying with it the discharge tube 27 but this movement will not open the valve until the top of the discharge tube comes in contact 80 with the bottom of the valve head, whereupon any further movement in the same direction will open the valve and the pump may then be operated to discharge oil from the pump to the receptacle. It will be seen that 85 during the discharging operation the several parts will be in the position shown in Fig. 4 so far as the nozzle assembly is concerned. The operation of the pump draws the oil from the container through the check valve 90 43 in the lower head 7 of the pump and at the same time forces the oil above the piston 1 out through the discharge nozzle. When the piston 1 is lowered the check valve 44 is opened and 43 is closed, thus forcing the 95 oil which has been previously drawn into the cylinder to pass through the valve 44, above the piston.

When the receptacle is withdrawn, the arm 19 instantly drops to its original position by 100 reason of the force of gravity and initially also by the pressure of the spring 21 upon the valve head 23. However, it will be noted that the valve head 23 will seat before the diaphragm has fully expanded and the further expansion of the diaphragm will tend to create a vacuum next to the valve head and prevent the oil remaining within the diaphragm and discharge tube from dripping out.

As shown in Fig. 5, the valve stem 32 does not extend to the bottom of the bore of the member 39 in which it is mounted and there is a space 41 between the lower end of the valve stem and the member 39 and therefore the member 39 may be moved upward a short distance before it contacts with the valve stem to lift the valve. In this form of nozzle the valve also closes before the member 39 has reached its lowest or normal position and the continued downward movement of the member 39 after the valve has closed, tends to create a vacuum around the valve head and holds the oil remaining below the valve head from dripping out of the discharge nozzle.

Having thus fully described my invention and its mode of operation, what I claim is:

1. In an oil-dispensing device, a pump

provided with means for conveying oil therefrom, a nozzle secured to said oil conveying means and comprising a member provided with an oil chamber and an outlet thereto, a valve adapted to open and close the outlet, an oil receiving chamber below said outlet and communicating therewith, means for opening the valve and contracting the oil receiving chamber while the valve is being opened, means for closing the valve, and means for expanding the oil receiving chamber after the valve is closed.

2. In an oil-dispensing device, a pump provided with means for conveying oil therefrom, an outlet for said oil-conveying means, a valve in said outlet, an oil receiving chamber below said outlet and communicating therewith, means for opening the valve and contracting the oil receiving chamber while the valve is being opened, automatic means for closing the valve, and means for automatically expanding the oil receiving chamber after the valve is closed.

3. In an oil-dispensing device, a pump provided with means for conveying oil therefrom, an outlet for said oil conveying means, a valve in said outlet, an oil receiving chamber below said outlet and communicating therewith, means for opening the valve and contracting the oil receiving chamber while the valve is being opened, means for closing the valve, and means for automatically expanding the oil receiving chamber after the valve is closed.

expanding the oil receiving chamber after the valve is closed.

4. In an oil-dispensing device, a pump provided with means for conveying oil therefrom, an outlet for said oil conveying means, a valve adapted to open and close said outlet, an expandible diaphragm below said outlet and adapted to receive oil from the outlet, a member adapted upon application of pressure thereto to compress said diaphragm and open the valve, means for automatically closing said valve when said pressure is released and before said diaphragm has reached the limit of its expansion.

5. In an oil-dispensing device, a pump provided with means for conveying oil therefrom, an outlet for said oil-conveying means, an oil receiving chamber below said outlet and communicating therewith, means for decreasing the capacity of the oil receiving chamber before the valve is open and then opening the valve and further decreasing the capacity of said oil receiving chamber, means for automatically closing the valve, and means for increasing the capacity of the oil receiving chamber after the valve is closed.

Signed at the city of New York, county of New York, State of New York, this 3rd day of March, 1925.

PAUL W. FENTON.
